CLAIM

The ornamental design for a medical imaging device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of the first embodiment of a medical imaging device, showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof; and

FIG. 7 is a top, front, right side perspective view thereof.

FIG. 8 is a front elevation view of the second embodiment of the medical imaging device of FIG. 1;

FIG. 9 is a rear elevation view thereof;

FIG. 10 is a top plan view thereof;

FIG. 11 is a bottom plan view thereof;

FIG. 12 is a left side elevation view thereof;

FIG. 13 is a right side elevation view thereof; and,

FIG. 14 is a top, front, right side perspective view thereof.

In the drawings, the broken lines depict portions of the medical imaging device that form no part of the claimed design.
